HARROW

Edward W. Ruffner, Mason, Ill., assignor of one-half to George I. Danks, Edgewood, Ill.

Application April 21, 1932. Serial No. 606,698

1 Claim. (Cl. 55—103)

The present invention relates to agricultural implements or machines in general and more particularly to new and useful improvements in harrows and has for one of its important objects 5 to provide, in a manner as hereinafter set forth, a harrow which is reversible and which comprises a novel construction, combination and arrangement of parts through the medium of which the harrow's teeth may be caused to be 10 sharpened when the harrow is in use.

Other objects of the invention are to provide 15 a harrow of the character described which will be simple in construction, strong, durable, efficient and reliable in use and which may be manufactured at low cost.

All of the foregoing and still further objects and advantages of the invention will become apparent from a study of the following specification, taken in connection with the accompanying 20 drawings wherein like characters of reference designate corresponding parts throughout the several views, and wherein:—

Figure 1 is a view in top plan of a harrow section constructed in accordance with the present 25 invention.

Figure 2 is a view in front elevation of the harrow section.

Figure 3 is a view in side elevation thereof.

Referring now to the drawings in detail, it will 30 be seen that the embodiment of the invention which has been illustrated comprises a pair of spaced, parallel, longitudinally extending beams 1 having openings 2 in their end portions so that the hitch (not shown) may be selectively engaged with either end of said beams 1. Between the beams 1 are provided the integral, relatively reversely disposed substantially V-shaped braces 3, the free ends of the legs of said braces being secured in any suitable manner, as by welding, to the beams 1. As best seen in Figure 1 of the drawings, the integrally connected apex portions of the braces 3, in conjunction with each other, define a substantially diamond-shaped plate.

Journalized for rocking movement transversely in the beams 1 are the staggered tooth bars 4 having anchored therein the depending teeth 5. Fixed to the intermediate tooth bar 4 and rising therefrom is a hand lever 6. Arms 7 are 40 fixed to the other tooth bars 4. The arms 7 are connected to the hand lever 6 for actuation thereby through the medium of a bar 8 which is pivotally connected to a lower portion of said lever and to the upper end portions of the arms. 45 It will thus be seen that all of the tooth bars

4 are connected to the hand lever 6 for simultaneous actuation thereby.

The reference numeral 9 designates a comparatively short intermediate longitudinal beam through which the tooth bars 4 rotatably extend, 60 said beam being immediately adjacent the arms 7 and the lever 6. A notched segment 10 rises from the intermediate beam 9 adjacent the lever 6 and is engageable by a latch means 11 operatively mounted on the lever for releasably 65 securing said lever in adjusted position.

In use, either end of the harrow section may constitute the forward end as said ends are of duplicate construction. Through the medium of the elements 6, 7 and 8, the tooth bars 4 may be 70 rocked to incline the teeth 5 in either direction, according to which end of the harrow is being used as the forward end. In this way, the teeth may be kept sharpened and will be caused to wear down evenly.

It is believed that the many advantages of a harrow constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

A harrow comprising spaced, parallel, longitudinal outer beams having openings in their end portions for connecting a hitch thereto, a comparatively short beam mounted intermediate the outer beams, staggered tooth bars journalized 90 for rocking movement in the beams, teeth mounted in the tooth bars, a hand lever fixed on an intermediate bar and rising therefrom, arms fixed on the other tooth bars and rising therefrom, a bar pivotally connected to the arms and to the lever for connecting the tooth bars together for movement in unison, a notch segment mounted on the intermediate beam, a latch on the lever operatively engageable with the segment for securing the lever in adjusted position, and integral, relatively reversely disposed, substantially V-shaped braces extending between the beams.

EDWARD W. RUFFNER. 105
